H. G. YETTER

LUG CLEANER

Filed March 10, 1928

Patented Jan. 22, 1929.

1,699,577

UNITED STATES PATENT OFFICE.

HARRY G. YETTER, OF BLANDINSVILLE, ILLINOIS.

LUG CLEANER.

Application filed March 10, 1928. Serial No. 260,664.

This invention relates to an attachment for cleaning between the lugs of tractor wheels and the like, one of the objects being to provide a device of this character which can be applied readily to a machine and which, after being set for use will trip automatically out of normal position if contacted by some unyielding obstruction lodged between the lugs, thereby avoiding injury.

Another object is to provide a scraper which will be supported out of contact with the wheels so that wear upon the parts is reduced to the minimum.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a side elevation of a portion of a wheel having the scraper supported adjacent thereto in position for use.

Figure 2 is a similar view showing the relative positions of the parts after the scraper has been tripped and brought to inactive position.

Figure 3 is a front elevation of the attachment.

Figure 4 is a section on line 4-4, Figure 1.

Figure 5 is a section on line 5-5, Figure 1.

Referring to the figures by characters of reference 1 designates an attaching plate having a flange 2 in which a stem 3 is mounted for rotation. This stem is extended from a crosshead 4 arranged between and suitably connected to ears 5 projecting upwardly from a frame 6. The lower portion of the frame 45 is forked as shown at 7 and has a guide block 8 mounted therein on a transverse shaft 9 journaled in the sides of the fork and rotatable with the block. This block 8 has a passage 10 extending longitudinally there-through and formed in the bottom of the passage is a longitudinal groove 11. A blade 12 is mounted to slide within the passage 10 and has a longitudinal rib 13 on its bottom face adapted to work within the groove 11. 50 As shown particularly in Figure 3 the sides of the blade 12 are cut away at 14, providing

a broad scraping portion 15 at one end of the blade and a broad head 16 at the other end. Stop pins 17 are detachably mounted in the blade 12 at opposite sides of the block 8 and serve to limit the sliding movement of the blade relative to the block. A coiled spring 18 is attached at one end to the bottom of the block 8 and at its other end to the bottom portion of the blade 12 near the scraping edge 65 thereof, this spring being extended under the block as shown particularly in Figure 1 and serving normally to pull the blade away from the wheel W with which it is designed to cooperate. Stop brackets 19 are provided at 70 the sides of the fork 7 and are adapted to lap beveled shoulders 20 formed at the sides of the head 16 where they project beyond the cutaway portions 14 of the blade 12. Screws 21 are carried by these brackets for 75 engaging the shoulders 20, thereby to hold the blade 12 in active position as shown for example in Figure 1. At this time the blade is held against the action of the spring 18 by a spring latch 22 fastened on the block 8 80 and having a depending head 23 which laps the outer end of the head 16 of the blade. This latch can be adjusted by providing a coiled spring 24 mounted thereon and on a threaded stem 25 extending loosely through 85 the latch. A nut 26 engages the stem and can be turned so as to increase or reduce the compression of the spring 24 and correspondingly increase or reduce the efficiency of the latch 22 as a blade retaining means. 90

A coiled spring 26' is mounted on one end of the shaft 9, one end of this spring being secured to the fork 7 while the other end is secured to a collar 28 adjustably mounted on the shaft. This spring is constantly under tension and serves to hold the blade 12 normally pressed against the stop screws 21. 95

Assuming that the parts are located as in Figure 1, it will be noted that, as wheel W rotates, the scraping edge of blade 12 will work between the parallel rows of lugs mounted on the periphery of the wheel, thus scraping out any accumulations of clay or the like between the lugs. It will be noted that, while the blade is in its normal position, the scraping edge thereof is held away from the periphery of the wheel W, a minute adjustment for this purpose being permissible by the use of the screws 21. Should an unyielding obstruction, such as a large stone, be carried against the edge of the scraper by the rotating wheel, the pressure exerted there-

by against the scraper will cause it to shift longitudinally against the head 23 which will yield under extreme force. This longitudinal movement of the blade will result in the withdrawal of the inclined or beveled shoulders 20 from contact with the screws 21. Consequently two actions take place automatically. As soon as the blade is pushed past the retaining head 23, the spring 18 will slide 10 the blade longitudinally away from the wheel W and as soon as the shoulders 20 are withdrawn from contact with the screws 21, the spring 26 will rotate shaft 9 and cause the blade 12 to swing upwardly from the position shown in Figure 1 to the position shown in Figure 2.

It will be noted that the scraping edge of the blade travels substantially in the direction in which the obstruction is moving during this collapsing operation so that there is no danger of any of the parts becoming jammed and broken.

It is intended to connect the attachment to a fender or any other rigid part of a tractor 25 in close proximity to the wheel W, a portion of the device to which the attachment is connected being indicated at F.

For the purpose of resetting the scraper it is merely necessary to swing the blade forwardly and downwardly approximately to 30 the angle illustrated in Figure 1 and then to shift the blade longitudinally toward the wheel until the free end of the head 16 passes the head 23. At this time the head will snap 35 into engagement with the blade and at the same time the shoulders 20 will be brought into position for engagement by the screws 21. Spring 18 will also be tensioned and increased tension will be added to the spring 40 26. With the parts thus reset the scraper can again be used until automatically released as heretofore explained.

It is to be understood that the jointed supporting structure made up of the flange 2, 45 cross-head 4 and frame 6 provides a means whereby the scraper can be shifted to any desired position relative to the wheel W after which the several joints can be tightened to hold the supporting structure against movement away from the position in which it has 50 been set.

What is claimed is:

1. The combination with a fork and a guide member pivotally mounted therein, of a scraping blade slidably mounted within and projecting from the guide member, yielding means for holding the blade normally retracted from active position within the guide member, means for engaging the blade for holding it projected to active position against the action of said yielding means, said holding means being releasable when subjected to excessive pressure from the blade.

2. The combination with a guide member 65 pivotally mounted, and means for connecting

the same to a support, of a blade slidably mounted in the guide member, yielding means for holding the blade normally projected to active position, said means being shiftable by the blade when subjected to excessive pressure, to release the blade, means for automatically shifting the blade longitudinally when released, and means controlled by said longitudinal movement of the blade for swinging the blade away from active position 75 during said longitudinal movement.

3. The combination with a supporting structure, of a guide member pivotally mounted therein, a scraping blade slidably mounted within and projecting from said member, yieldable means engaging the blade for holding it normally projected, said means being adapted, when subjected to excessive pressure from the blade, to release the blade, spring means for shifting the blade longitudinally when released, cooperating means on the supporting structure and blade for holding the blade against swinging movement, when the blade is in normal or projected position, and means for automatically swinging the blade when moved longitudinally away from normal position.

4. The combination with a supporting structure, of a guide member pivotally mounted therein, a scraping blade slidably within and projecting from the guide member, means for engaging the blade for holding it projected to active position, said blade, when subjected to excessive longitudinal pressure, constituting means for shifting the holding means to release the blade, a spring for shifting the blade longitudinally when released, an adjustable stop carried by the supporting structure, means on the blade cooperating with the stop for holding the blade against swinging movement while in active position, and means for automatically swinging the blade away from active position during the longitudinal movement thereof.

5. The combination with a wheel having 110 lugs and a structure adjacent the wheel, of a jointed supporting structure adjustably connected to the first named structure, a guide member carried by the jointed supporting structure and mounted for pivotal movement, 115 a scraping blade slidably mounted within the guide member, a latch engaging the blade for holding it normally projected to active position in close proximity to the wheel, adjustable stop means carried by the supporting structure and cooperating with the blade for holding the blade against swinging movement in one direction, means for automatically swinging the blade in said direction when disengaged from the stop, said blade, when thrust longitudinally by an unyielding obstruction carried by the wheel, constituting means for disengaging the holding means from the blade, and releasing the blade from the stop, and means for automatically shifting the 125 130 135

blade longitudinally when released from its holding means.

6. The combination with a wheel having lugs and a structure adjacent the wheel, of a 5 guide member pivotally mounted, adjustable means for connecting said guide member to the said structure, a scraping blade slidably mounted within the guide member, a latch for holding the scraping blade normally projected to active position relative to the periphery of the wheel, an adjustable stop cooperating with the blade for holding it against swinging movement in one direction, said blade, when subjected to longitudinal 10 pressure by an unyielding obstruction carried by the wheel, constituting means for shifting the latch to release the blade, and a spring 15 for automatically shifting the blade longi-

tudinally when released from the latch, thereby to disengage the blade from the adjustable 20 stop.

7. The combination with a wheel and a lug, and a structure adjacent thereto, of a scraping blade connected to said structure and supported with its scraping blade normally close 25 to but out of contact with the periphery of the wheel, and separate means released by the application of excessive pressure against the scraping edge of the blade for shifting the blade longitudinally away from the wheel 30 and swinging said blade upwardly and backwardly relative to the wheel.

In testimony that I claim the foregoing as my own, I have hereto affixed my signature.

HARRY G. YETTER.
